UNITED STATES PATENT OFFICE.

OVERTON WINSTON, OF MINNEAPOLIS, MINNESOTA.

HEADLIGHT.

1,319,824.

Specification of Letters Patent. Patented Oct. 28, 1919.

Application filed March 9, 1917. Serial No. 153,539.

To all whom it may concern:

Be it known that I, OVERTON WINSTON, a citizen of the United States, residing at Minneapolis, in the county of Hennepin and State of Minnesota, have invented certain new and useful Improvements in Headlights; and I do hereby declare the following to be a full, clear, and exact description of the invention, such as will enable others skilled in the art to which it appertains to make and use the same.

My present invention relates to headlights and is particularly directed to the provision of an improved form of lens and to an improved relative arrangement thereof, in respect to a concave reflector and electric light source within the latter.

In the accompanying drawings which illustrate the invention, like characters indicate like parts throughout the several views.

Referring to the drawings:

Figure 1 is a vertical section showing a headlight embodying my invention and wherein a two-filament light bulb is employed as a means for shifting the light source from the axis of the reflector to a point vertically above said axis:

Fig. 2 is an elevation looking at the inner face of the lens;

Fig. 3 is a fragmentary view in inner face elevation showing, on an enlarged scale, one of the prismatic sections of the lens;

Fig. 4 is a section on the line 4—4 of Figs. 2 and 3;

Figs. 5 to 15, inclusive, are sections taken on the correspondingly marked section lines on Fig. 3;

Fig. 10^a is an enlargement of the prismatic section shown in Fig. 10 and indicating the travel of the ray of light in passing thereto, therethrough and therefrom; and

Fig. 16 is a view corresponding to Fig. 1 but showing a headlight having a single filament light bulb.

Of the parts of the headlight, the numeral 17 indicates the casing, the numeral 18 the clamping ring thereof, the numeral 19 the concave reflector, the numeral 20 the electric light bulb and the numeral 21 the lens. The reflector 19 is preferably a hyperbolic reflector and it is provided with an axial passage through which the shank of the light

bulb 20 projects and is held by a suitable support. This bulb support, so far as this invention is concerned, may be of any suitable construction, but as shown, comprises a shank engaging sleeve 22 and a tubular socket 23 screwed into a flanged hub 24 secured to the back of the reflector.

The bulb shown in Fig. 1, is a two-filament bulb, the one filament having its hot spot at *a* and the other having its hot spot at *b*. The point *a* is at the axis of the reflector and preferably, also, at the focal center thereof. The point *b* is vertically above the axis of the reflector. By means of a three-lead circuit 25, 26 and 27, which includes a battery 28, and switches 29 and 30, either of the two filaments *a* and *b* may, at will, be energized and used as the light source of the headlight.

In the headlight illustrated in Fig. 16, the light bulb 20 is provided with a single filament *c*, the hot spot of which is at the axis of the reflector and preferably also at the focal center thereof. This filament is connected to a battery or source of electrical energy 31, by leads 32, in one of which is a switch 33.

We will not consider the novel construction of the lens, the preferred form of which is illustrated in the drawings and which, described in detail, is as follows:

One face of the lens, preferably its inner face, is formed with prismatic surfaces that extend horizontally across that face of the lens. The beveled surface of all of the prisms diverge downwardly from the plane of the lens, but the different prisms have a different bevel.

The prisms having the greatest maximum bevel are approximately at a horizontal line that intersects the axis of the lens and headlight, and in the lens illustrated, these horizontal prisms have a maximum downward divergence or bevel of nineteen degrees to the plane of the lens. The bevel of the successive prisms, in directions both vertically upward and vertically downward from the said horizontal line, progressively decrease, preferably in a constant order of succession. For example, with the variation in the maximum bevel of the successive prisms may be as indicated by the small numerals marked on the curved line in Fig. 2, by reference to

- which it will be noted that the uppermost prisms have a maximum bevel of only one degree to the plane of the lens and the bevel of the prisms above the horizontal central line increase in a downward direction one degree, each over the other, while the prisms that are below the said horizontal line progressively decrease in a downward direction.
- 10 Each bevel has a maximum bevel at points midway between its extremities and its longitudinal center. In Fig. 2, the approximate points of maximum bevel are indicated by the points where the small numerals are marked thereon, and in directions, both to the right and left of these points, the said prisms have progressively decreasing bevel, and in the preferred arrangement, the bevel diminishes to zero at the latter extremities 20 of the said prisms, and at points on a vertical line that intersects the axis of the lens. Instead of diminishing to zero at points stated, the said bevels might diminish to an angle of less than the respective maximum 25 angles of the said prisms.

With the above described arrangement, the prisms that are nearest to the horizontal line intersecting the axis of the lens give the greatest downward deflection to the 30 light rays, but in any particular prism the greatest deflection of the light produced thereby will be from points midway between its extremities and a line that intersects the said prisms and the axis of the 35 lens. This gives a general downward deflection of the light beams with a minimum downward deflection from the extremities of the prisms and from the central portions of the prisms and a maximum downward deflection on curved lines that intersect the prisms midway between their extremities 40 and the said vertical central line.

In Fig. 1 the lighter ray lines indicate the light rays when the light source is at 45 *a*, and the heavier ray lines the rays when the light source is at the vertically offset point *b*. It will thus be observed that the light beam is given a greater downward deflection when the light source is at *b* than 50 when the light source is at *a*.

Obviously, the best light beam for country road driving is produced when the light source is at *a* and the best light beam for city street driving is produced when the 55 light source is at *b*. It is not desirable to give this great downward deflection to the less intense rays from the upper portion of the reflector as is given to the more intense rays from the back of the reflector. It is 60 desirable to get a maximum amount of intense rays on the road, but it is also desirable to diffuse some of the less intense light rays so as to light up objects above the road and at the sides of the road, and for this reason,

the prisms nearest to the horizontal plane 65 of the axis of the reflector are given greatest bevel and those nearest the top and preferably also those nearest the bottom are given decreased or less angle.

In the use of a headlight with an ordinary reflector adjusted so as to throw approximately the lower half of the light beam upon the ground, which is quite a common arrangement, the lower half of the light beam will be distributed over many 70 hundreds of square feet of road surface, and per unit of surface, the road will be given but a very small percentage of light, as compared with the amount of light thrown upon a vertical object in the road, by the 75 upper half of the light beam. This is a result just reverse from that desired. An ideal arrangement would be one in which there would be at least as much light, per unit of surface, thrown upon the road, as 80 there would be upon a vertical object above the road; and such an arrangement, obviously, requires very much the greater part 85 of the light beam to be distributed on the ground and a very minor part of the light 90 beam to be diffused above the road. This ideal result is closely approximated by the use of the improved lens above described, which, as already stated, produces very great downward deflection of the more intense 95 rays of the light beam and diffuses some, or a minor part of the less intense light rays above the road.

What I claim is:

1. A lens for headlights having a group 100 of parallel prisms beveled in the same general direction, said prisms, individually, having maximum bevel at points intermediate of the rim of the lens and a diameter thereof perpendicular to the edges of 105 said prisms and having decreasing bevels progressively in both directions from the respective points of maximum bevel.

2. A lens for headlights having a group 110 of parallel prisms beveled in the same general direction, and among themselves, in a circumferential direction, having progressively varying bevels, said prisms, individually, having maximum bevel at points intermediate of the rim of the lens, and a 115 diameter thereof perpendicular to the edges of said prisms, and having decreasing bevels progressively in both directions from the respective points of maximum bevel.

3. A lens for headlights having a group 120 of horizontal prisms beveled in the same general direction, said prisms, individually, having maximum bevel at points intermediate of the rim and the vertical diameter of said lens, and having decreasing bevels 125 progressively in both directions from the respective points of maximum bevel.

4. A lens for headlights having a group

of horizontal prisms beveled in the same general direction, said prisms, individually, having maximum bevel at points intermediate of the rim and the vertical diameter of said lens, and having decreasing bevels progressively in both directions from the respective points of maximum bevel, the said prisms, among themselves, in a direction circumferentially from the upper toward the lower portion of the lens having progressively increasing bevel.

5 In testimony whereof I affix my signature in presence of two witnesses.

OVERTON WINSTON.
